UNITED STATES PATENT OFFICE.

MELVILLE CLARK, OF CHICAGO, ILLINOIS.

ORGAN-ACTION.

SPECIFICATION forming part of Letters Patent No. 439,111, dated October 28, 1890.

Application filed April 22, 1889. Serial No. 308,216. (No model.)

To all whom it may concern:

Be it known that I, MELVILLE CLARK, a citizen of the United States, residing at Chicago, county of Cook, and State of Illinois, have 5 invented certain new and useful Improvements in an Organ-Action, which is fully set forth in the following specification, reference being had to the accompanying drawings, forming a part thereof.

10 This invention relates particularly to the action of an organ having pedal-keys for operating a certain set of reeds.

In the drawings, Figure 1 is a vertical section through an organ, showing the several 15 parts which constitute my invention in position such that the manual-reeds are not operated by the pedal-keys. Fig. 2 is a similar section showing the parts in such position that the pedal-keys operate the manual-reeds.

20 Fig. 3 is an inverted plan of the action. Fig. 4 is a detail section through the action at the line 4 4 on Fig. 3, omitting all parts except those which relate to the manual-coupling mechanism.

25 Fig. 5 is a section at the line 5 5 on Fig. 3, showing only the parts which relate to the pedal-coupling mechanism. Fig. 6 is a longitudinal section at the line 6 6 on Fig. 2. Fig. 7 is an end view of the same part shown in 30 Fig. 6. Fig. 8 is a sectional detail elevation of the pedal-key-lever valve-rod, showing means for adjusting its length. Fig. 9 is a detail plan of mechanism by which the fulcrum of the levers which connect the pedal and 35 manual-action is shifted.

The drawings represent an organ having four sets of reeds arranged in a single block controlled by two sets of valves, each valve 40 of each set controlling a reed in each of two of the sets of reeds, and two sets of reeds being subject to the action of one swell, and the other two to the action of another swell, each set of reeds being separately controlled by a mute, the construction in all these respects 45 being the usual one. There is also shown a set of sub-bass reeds in a separate block, wherein the reeds are arranged vertically on account of their size, and are controlled each by a valve, the entire set being further controlled by a mute and subject to the action of 50 a swell in the usual manner.

Referring to the parts by letter, A represents the organ-case; B, the bellows.

C is the bellows-operating lever; C', the strap connecting the lever to the bellows. 55

D is the action base-plate, which forms also the bottom of the valve-chamber E, which is peripherally bounded and closed by the sides and ends E', and has the top plate F, upon which are supported the blocks G and N, in 60 which are formed the reed-chambers, and upon which are supported the several parts to which the swells are connected. Through the top plate F are formed the valve-openings F' F', closed by the valves F² F²⁰, which 65 are provided with the usual springs f² f²⁰, retaining the valves on their seats.

G' g' are reeds of two sets of reeds located on one side of the block G.

G² g² are reeds of two sets of reeds similarly located on the opposite side of the block. 70

H h are mutes, which control, respectively, the sets of reeds represented by G' and g'.

H' h' are mutes, which control, respectively, the sets of reeds represented by the reeds G² 75 and g².

I I² are swells, which affect, respectively, the sets of reeds on the opposite sides of the block G.

L represents the lower bank of keys of the 80 manual, and L' represents the upper bank.

K and K' represent, respectively, the push-rods from the keys L and L' to their respective valves f² and f²⁰. The usual stop mechanism is provided (but is not herein shown 85 because not specifically a part of this invention) for operating the several mutes to either stop or permit the action of the several sets of reeds, as desired.

The action as thus far described is the customary one. To the side E' of the valve-chamber E there is hinged the lip or broad lever R, to the free edge of which at r are pivoted the levers S, one for each of the valves F², and located underneath said valves 95 respectively. The other end of each of the levers S opposite that at which it is pivoted to the lip R is connected to the valve F²⁰, corresponding to the valve F² under which said lever is located. The connection illustrated 100 is made by means of a bracket a, fastened to the valve F²⁰ almost directly underneath the

point at which the push-rod K engages the said valve on the upper side, and that bracket which is bent horizontally at the lower end receives and supports in said horizontal portion the end of the lever S. From each of the levers S there projects upward a stud S', which receives the contact of the valve F² when the parts are in proper position, as will be hereinafter explained. Such position is illustrated in Fig. 2, and depends upon the position of the lip R, which, for the purpose of adjustment, has at one end the short arm R' projecting from its free edge near the end of the valve-chamber. To the valve-chamber wall there is pivoted the lever T, two small brackets T' projecting downward from the top plate of the chamber in order to afford pivotal support for said lever. One end of this lever projects underneath the arm R' of the lip R, and thereby upholds said lip, while the other end is exposed to the action of a crank-rod U, which is pivoted to the top plate of the chamber, having its crank-arm U' acting upon the lever F. When the crank-rod U is rocked to throw its crank U' downward, such movement depresses the end of the lever T, which said crank operates, lifting the other end, and thereby lifting the free edge of the lip R, bringing said lip into the position shown in Fig. 2. In this position the lip R holds the levers S, which are attached to its free end up in the position shown in said Fig. 2, wherein the stud S' contacts the underside of the valve F² when said valve is on its seat. It will be obvious that when the key which operates said valve is depressed and the valve forced off its seat by downward movement it will in that movement force downward the lever S, whose forward end is fixed at its pivotal connection with the lip R, so that its rear end, which rests on the bracket a, will experience the full downward movement, and in and by that movement will pull down the valve F²⁰, which in the absence of such coupling device would be subject only to the action of the key L'. By this means the keys in the lower bank can be made to operate any of the reeds which ordinarily are subject only to the action of the keys in the upper bank, and by opening all the mutes H, h, H', and h', each key in the lower bank may operate all four of the reeds G' g' G² g², and by closing one or more of the mutes the tone may be limited to one or a combination of one or more of said reeds at will. Thus the lower bank of keys may be made to produce tones from only the reeds, which are ordinarily operated by the upper bank to the exclusion of the reeds directly pertaining to the lower bank, if desired. I will now describe the mechanism pertaining to the pedal-keys and their coupling with the manual-action.

Q Q' are the pedal-keys, which act upon levers P, which are connected by rods O to the valves N³, which control the sub-bass reeds N', having their chambers, respectively, in the block N, and being further controlled by

the mutes N² and subject to the action of the swell N⁵. The rods O pass up through the valve-chamber E, above which the block N, 70 having the pedal-reeds is located. In order that the aperture through which this rod passes may not cause any appreciable waste of air from the valve-chamber, I make the portion of the rod which penetrates the upper 75 and lower walls of the chamber of comparatively slender wire O'. This wire is screwed into the upper end of the lower portion of the rod O, which is made of wood, and is provided with a stop O² below the bottom of the valve-chamber to limit the upward stroke of the rod under the operation of the pedal-keys. The hole in the bottom of the valve-chamber through which the portion O' of the rod extends is considerably larger than the rod, to 80 prevent friction and noise in the action. Over the row of these holes there is secured a strip of leather or other similar flexible and non-resonant substance O², which is pierced with holes, through which the wire portion 85 O' of the rods passes, fitting closely. Upon the rod—that is, upon the wire portion O' above the bottom of the valve-chamber—there is made fast a stop O³ in such position that it rests upon the upper surface of the valve-chamber bottom, contacting at that point the leather strip O² above mentioned, when the valve N³ is on its seat, with the upper end of the rod N⁴ contacting its under surface, but not upholding it. To each of the valves F² 90 there is secured a downwardly-projecting screw-eye b, for which an aperture is made in the lever S, so that it may project downward through it. In the eye b', which stands below the lever S, there is received one end of 95 the lever V, the other end of which stands closely adjacent to the rod O O', and preferably is forked at the end, so that it embraces the rod, and is thereby kept adjacent to it. A fulcrum for these levers is provided in the following manner: To the top plate F of the valve-chamber there is secured the downwardly-projecting bracket W', to the lower end of which is hinged the lip or broad lever W, at the free end of which the levers V are pivoted. A convenient mode of pivoting the levers and forming their fulcrum is that illustrated, which consists of a bar V², perforated to allow the levers to be inserted through it, the apertures being V-shaped both above and 100 below, so that the levers resting upon the angles thus formed are provided with an accurate fulcrum, and at the same time have capacity for longitudinal movement through the bar, slight movement of that nature being requisite to that action, as will hereinafter appear. Springs C C are secured to the plate F, acting upon the lever W, tending to uphold it in the position shown in Fig. 1, wherein it is stopped upwardly by contact 105 with the block X, which also affords means of holding the springs f²⁰. To prevent any noise in the contact of the lever W with the block, the latter is covered with a non-reso-

nant sheet x . On the under surface of the upper plate F of the valve-chamber there is journaled the cranked rock-shaft Y , having several cranked portions Y' , which bear upon the upper surface of the lip when the latter is in the position shown in Fig. 1, said cranked portions being long enough so that when the shaft is rocked in its bearings to throw said cranks downward they will force the lever W down into the position shown in Fig. 2. In the first position (shown in Fig. 1) the rear forked end V^3 of the lever V stands out of range of the vertical action of the stop O^2 on the pedal-key-lever rod, and when the lever W occupies this position the action of the pedal-keys will produce no action of any of the manual-reeds, but only of the pedal-reeds N^3 . When, however, the lever W is forced into the position shown in Fig. 2, the end V^3 of the lever V rests on the stop O^2 . When the latter is in its lowest position, and when these parts are in this position, the operation of the pedal-keys forcing upward their rods respectively, will carry up with them, by means of the stops O^2 , the rear end of the levers V , and thereby depressing the forward end of said levers will, by means of the screw-eyes b , cause the levers to pull down the valves F^2 . If, now, the lip R is in the position shown in Fig. 2, in which the levers S operate as a coupling between the valves F^2 and F^{20} , the action described opening the valves F^2 will also open the valves F^{20} , and thereby bring into action so many of the reeds contained in the block G and pertaining to the manual-keys as are not stopped by their respective mutes, thus permitting the combinations with the pedal-reeds operated by the pedal-keys of any one, two, or three, or all of the reeds G', g', G^2, g^2 .

An important merit of the construction employed as above described is the simplicity of the mechanism of the pedal-bass action, which results from extending directly from the pedal-levers to the valves which control the pedal-reeds the valve-actuating rods O . In order that these rods may extend thus directly from the levers to the valves and constitute the sole mechanical element in the action between the levers and the valves, these rods must pass through the valve-chamber or wind-chest E , and in order that this construction may not diminish the effectiveness of the wind-chest by making it leak the use of the packing-strips O^2 is desirable, and in order that the rods passing through this strip, and fitting so closely therein as to prevent leakage around them, may not be too much hindered in their action by the same, the reduction of the diameter of the rod at the part that passes through the packing-strip is also desirable. In order that the friction of the wire portion O' of the rod O where it passes the leather may not in any event prevent the valves closing properly, I provide the springs N^8 , which are suitably secured at one end in the guide-bars n^8 , and at the other end are con-

nected, respectively, to the rods O' , tending to depress the rods as soon as they are relieved from the control of the pedal-keys. 70

By means of my construction of the pedal-action I am able to avoid all openings through the swell N^5 , which are necessary when the valves are operated by mechanism which reaches them without passing through the wind-chest, and by thus preserving the swell without mutilation the accurate voicing of the pedal-bass which otherwise is impossible is made possible. 75

I claim—

1. In an organ-action, in combination with the manual-keys and the reed-valves which they respectively operate, the pedal-key levers, the pedal-lever rods, and the valves of the pedal-bass which they respectively operate, a system of levers which at one end connect with and are adapted to operate the valves which are also operated by the manual-keys and at the other end stand adjacent to the pedal-lever rods, said rods having stops 85 adapted to engage the adjacent levers when the rods are moved to open their respective valves, substantially as set forth. 90

2. In an organ-action, in combination with the manual-keys and the reed-valves which they respectively operate, the pedal-key levers, the pedal-lever rods, and the valves of the pedal-bass which they respectively operate, a system of levers which at one end connect with and are adapted to operate the valves which are also operated by the manual-keys and at the other end stand adjacent to the pedal-lever rods, said rods having stops 95 adapted to engage the adjacent levers, respectively, said levers having a fulcrum movable a sufficient distance to carry the ends of the levers which are adjacent to the pedal-key-lever rods out of range of the stops on said rods, respectively, substantially as set forth. 100

3. In combination with the manual-keys and the valves which they directly operate, coupling mechanism and the valves which the directly-actuated valves operate through such coupling mechanism, the pedal-key levers and the rods by which they operate their valves, respectively, and a system of levers which at one end connect with and are adapted to operate the valves which are directly actuated by the manual-keys and at 115 the other end stand adjacent to the pedal-lever rods, said rods having stops adapted to engage the adjacent levers, respectively, when the rods are moved to open their valves, respectively, substantially as set forth. 120

4. In an organ-action, in combination with the manual-keys and the valves which they directly operate, coupling mechanism and the valves which the directly-actuated valves operate through such coupling mechanism, the 130 pedal-key levers and the rods by which they operate their valves, respectively, a system of levers which at one end connect with and are adapted to operate the valves which are di-

- rectly actuated by the manual-keys, said levers at the other end standing adjacent to the pedal-lever rods, said rods having stops adapted to engage the adjacent levers, respectively, said levers having a fulcrum movable sufficient distance to carry the ends of the levers adjacent to the pedal-key-lever rods out of range of the stops on said rods, respectively, substantially as set forth.
- 15 5. In combination with the manual-keys, valves which directly and indirectly operate the several sets of reeds which said valves control, the mutes pertaining to said sets of reeds, respectively, and a system of levers which at one end connect with and are adapted to operate the valves which are also operated by the manual-keys and at the other end stand adjacent to the pedal-lever rods, said rods having stops adapted to engage the adjacent levers when the rods are moved to open their respective valves, whereby the pedal-keys may be made to operate at will corresponding reeds in any one or more of the sets which pertain to the manual-keys, substantially as set forth.
- 20 6. In combination with the manual-keys, valves which directly and indirectly operate the several sets of reeds which said valves

control, the mutes pertaining to said sets of reeds, respectively, and a system of levers 30 which at one end connect with and are adapted to operate the valves which are also operated by the manual-keys and at the other end stand adjacent to the pedal-lever rods, said rods having stops adapted to engage the adjacent levers, respectively, said levers having a fulcrum movable a sufficient distance to carry the end of the levers which is adjacent to the pedal-key-lever rods out of range of the stops on said rods, respectively, substantially 35 as set forth.

7. In an organ-action, in combination with the valves which pertain to the reeds operated by the manual-keys, the wind-chest or valve-chamber in which said valves are contained, 40 the valves pertaining to the pedal-reeds, and the rods which actuate said valves extending through said wind-chest, substantially as set forth.

In testimony whereof I have hereunto set 45 my hand, in the presence of two witnesses, at Chicago, Illinois, this 26th day of March, 1889.

MELVILLE CLARK.
